(57) **CLAIM**

The ornamental design for the foam roller for physical training, as shown and described.

DESCRIPTION

FIG. 1 is a perspective view of a foam roller;

FIG. 2 is a front view of the foam roller;

FIG. 3 is a rear view of the foam roller;

FIG. 4 is a left side view of the foam roller;

FIG. 5 is a right side view of the foam roller;

FIG. 6 is a top plan view of the foam roller; and,

FIG. 7 is a bottom view of the foam roller.

1 Claim, 6 Drawing Sheets
